US00D801966S

(12) **United States Design Patent** (10) **Patent No.:** **US D801,966 S**
(45) **Date of Patent:** **** Nov. 7, 2017**

(54) **DATA STORAGE DEVICE**

(71) Applicant: **Western Digital Technologies, Inc.**,
Irvine, CA (US)

(72) Inventors: **Steven T. Peng**, Irvine, CA (US);
Takashi Kono, Monterey Park, CA
(US)

(73) Assignee: **Western Digital Technologies, Inc.**,
Irvine, CA (US)

(**) Term: **15 Years**

(21) Appl. No.: **29/536,660**

(22) Filed: **Aug. 18, 2015**

Related U.S. Application Data

(62) Division of application No. 29/455,869, filed on May 24, 2013, now Pat. No. Des. 737,818.

(51) **LOC (10) Cl.** **14-02**

(52) **U.S. Cl.**
USPC **D14/365**

(57) **CLAIM**

The ornamental design for a data storage device, as shown
and described.

DESCRIPTION

FIG. 1 is a top, front and side perspective view of an
embodiment of a data storage device embodying the new
design.

FIG. 2 is a first side view thereof.

FIG. 3 is a second side view thereof.

FIG. 4 is a front view thereof.

FIG. 5 is a back view thereof.

FIG. 6 is a top view thereof; and,

FIG. 7 is a bottom view thereof.

Broken lines are used to illustrate features of the data storage
device which form no part of the claimed design.

1 Claim, 4 Drawing Sheets
